(57) **CLAIM**

An ornamental design for a “bottle,” as shown and described.

DESCRIPTION

FIG. 1 is a front perspective view of the bottle;
FIG. 2 is a front elevation view of the bottle;
FIG. 3 is a rear elevation view of the bottle;
FIG. 4 is a right side view of the bottle;
FIG. 5 is a left side view of the bottle;
FIG. 6 is a top view of the bottle;
FIG. 7 is a bottom view of the bottle;
FIG. 8 is an environmental perspective view including the bottle; and,
FIG. 9 is an alternative front perspective view of the bottle. The broken lines shown in the drawings represent portions of the bottle or environment that form no part of the claimed design.
